United States Patent Office

Des. 206,407
Patented Dec. 6, 1966

206,407

JUG

Robert E. A. Sharp, Sarnia, Ontario, Canada, assignor to
The Dow Chemical Company, Midland, Mich., a cor-
poration of Delaware

Filed Sept. 20, 1965, Ser. No. 87,081

Term of patent 14 years

(Cl. D58—5)

Fig. 1

Fig. 2

Fig. 3

Fig. 4

Fig. 5

Fig. 6

Fig. 7

FIGURE 1 is a front elevational view of a jug showing my new design;

FIGURE 2 is a side elevational view thereof, as seen from the right of FIGURE 1;

FIGURE 3 is a rear elevational view thereof;

FIGURE 4 is an elevational view thereof, as seen from the right edge of FIGURE 1 and showing the full handle in side elevation;

FIGURE 5 is a top plan view thereof;

FIGURE 6 is a bottom view thereof; and

FIGURE 7 is an elevational view like FIGURE 4 of a modified form of a jug without bands therearound.

I claim:

The ornamental design for a jug, substantially as shown.
